CLAIM

The ornamental design for a vase, as shown and described.

DESCRIPTION

FIG. 1 is a perspective view of a vase showing the new design;

FIG. 2 is a front elevational view of the vase of FIG. 1;

FIG. 3 is a rear elevational view of the vase of FIG. 1;

FIG. 4 is a left elevational view of the vase of FIG. 1;

FIG. 5 is a right elevational view of the vase of FIG. 1;

FIG. 6 is a top plan view of the vase of FIG. 1;

FIG. 7 is a bottom plan view of the vase of FIG. 1; and,

FIG. 8 is cross sectional view of the vase of FIG. 1 taken along the line 8-8 in FIG. 2.
